L. H. MCKEE
WOODEN RECEPTACLE

Filed Jan. 15, 1921

FIG. 1.

FIG. 2.

FIG. 3.

Inventor

LLOYD HAWLEY MCKEE

By Ogle R. Singleton,

Attorney

UNITED STATES PATENT OFFICE.

LLOYD HAWLEY MCKEE, OF FORT WORTH, TEXAS.

WOODEN RECEPTACLE.

Application filed January 15, 1921. Serial No. 437,456.

To all whom it may concern:

Be it known that I, LLOYD HAWLEY MCKEE, a citizen of the United States, residing at Fort Worth, in the county of Tarrant and State of Texas, have invented certain new and useful Improvements in Wooden Receptacles, of which the following is a specification.

My invention consists in a new and useful improvement in wooden receptacles and is designed more particularly to provide a coop for confining fowls or small animals for exhibition or transportation, and a crate for packing and transporting various articles. My invention provides a slatted coop or crate which is of very durable construction and which affords great ease in handling.

The invention is embodied in the details of construction illustrated in the drawings and hereinafter fully described, but I do not consider my invention limited to the specific embodiment herein set forth and refer for its scope to the claims appended hereto.

In the drawings:

Figure 1 is a top plan view of the device. Figure 2 is a side elevation of the device. Figure 3 is an end elevation of the device.

The specific embodiment of my invention disclosed in the drawings comprises a coop or crate having a solid rectangular bottom 1 and four corner posts 2, substantially triangular in cross-section, each having two right-angularly disposed faces 2^a located parallel with one side and one end of the bottom 1 respectively, and a beveled face 2^b. Four squared posts 3 are located at the middle points of the sides and ends of the bottom 1, and a squared center post 4 is placed at the center of the bottom 1. The posts 2 and the posts 3 are so placed in relation to the bottom 1 as to permit the bottom side slats 5 and the bottom end slats 6 to be fastened to the outside of said posts and lie flush with the sides and ends of the bottom 1. The ends of the side slats 5 enclose the end slats 6 which are slightly greater in thickness than the side slats 5. Top side slats 7 and top end slats 8 are fastened upon the outside of the posts 2 and the posts 3 with their upper edges lying flush with the tops of said posts. The slats 7 are the same size as slats 5 and slats 8 are the same size as slats 6. Between the side slats 5 and 7 there are placed a number of

side slats 9, two being shown in the drawings. Between the end slats 6 and 8 are placed a number of end slats 10, two being shown in the drawing. These slats 9 at 60 their ends enclose the slats 10, and as the slats 10 are of less thickness than the slats 6 and 8, the slats 9 are slightly less in length than the slats 5 and 7. Two cross slats 11 extend between the side slats 5 and 7 respectively and are fastened to the two posts 3 located at the middle points of the sides of the bottom 1, and to the post 4 located in the center of the bottom 1. A number of cross slats (not shown in the drawing) are 70 placed between the top and bottom cross slats 11, thus dividing the coop or crate into two equal sized compartments. A number of top slats 12, four being shown in the drawing, form a cover for the coop or crate. These slats 12 are fastened upon the top end slats 8 and the top cross slat 11. The two outside top slats 12 are so placed as to be spaced from the top side slats 7 but are sufficiently near to the sides of the coop or 80 crate as to pass over the tops of the corner posts 2 and the posts 3 located at the middle of the sides. A middle top slat 13 is located above the posts 3 located at the middle points of the ends, and above the center 85 post 4, and received in slots 8^b in the end slats 8 and a slot 11^a in the top cross slat 11. The posts 3 and the post 4 beneath this top slat 13 are reduced in length sufficiently to allow this slat 13 to rest slidably in the 90 slots 8^c and slot 11^a. Metal straps 8^c confine the slat 13 in the slots 8^b and metal strap 11^b confines the slat 13 in the slot 11^a. This slat 13 is not fastened to the posts as are the other slats and so may be withdrawn 95 endwise to afford independent access to either compartment of the coop or crate.

Between the corner posts 2 and the middle post 3, each of the top side slats 7 is provided with slightly reduced portions 100 formed by rounding off the edges of the slat to form a smooth-surfaced hand grip 7^a at two points upon each side of the coop or crate. The use of these grips 7^a is facilitated by the space afforded between the side 105 slats 7 and the outer top slats 12.

Between the corner posts 2 and the middle post 3, each of the end slats 8 is provided upon its under-side with an arcuate recess to form a smooth-surfaced hand grip 8^a at 110 two points upon each end of the coop or crate. The use of these grips 8^a is facil-

tated by the reduction of the thickness of the slats 10 in comparison with the thickness of the slats 8.

Having described my invention, what I claim is:

In a wooden receptacle, the combination of a bottom member; a plurality of posts attached to said bottom member; end, side and top slats attached to said posts, the out-

ermost top slat on each side being spaced 10 from the topmost side slat, and said topmost side slat being provided with reduced portions at points on its upper and lower edges to provide hand grips.

In testimony whereof I affix my signature.

LLOYD HAWLEY McKEE.
